UNITED STATES PATENT OFFICE.

MYRON F. HILL, OF NEW YORK, N. Y.

SHIP.

1,405,844.

Specification of Letters Patent.

Patented Feb. 7, 1922.

Application filed April 18, 1919. Serial No. 291,124.

To all whom it may concern:

Be it known that I, MYRON F. HILL, citizen of the United States, resident of the city, county, and State of New York, have invented an Improvement in Ships, of which the following is a specification.

My invention relates to cast steel ships and particularly to joints and methods of assembly.

10 In the drawings:—

Fig. 1 shows a view of the midship section.

Fig. 2 shows an intermediate transverse floor.

15 Fig. 3 shows a longitudinal section through a portion of the tank, or double bottom.

Fig. 4 shows the ends of keel sections to be joined.

Fig. 5 shows the joint between the tank top and a transverse frame.

20 Figs. 6 and 7 show the stanchion caps for the upper and shelter decks.

Fig. 8 shows the joint between the ends of longitudinals through a deck beam or floor or bulkhead.

25 Fig. 9 shows a sectional view of part of a hatchway for the shelter deck.

Fig. 10 shows a part of a hatchway for the upper deck.

Fig. 11 shows a portion of a shell expansion.

30 Fig. 12 shows in perspective view a joint suitable for use in the shell, tank top, and decks, also if desired between bulkhead and other castings.

35 Fig. 13 is a section of Fig. 12 down the line 13.

In Fig. 1 is shown the keel casting 14 having at the top flanges 15 to which are connected the edges of tank top sections 16. It 40 has a bulb 15^a for convenience in pouring, in accordance with principles set forth in my application Serial No. 267,480 $\frac{1}{2}$. The keel is stiffened with stiffeners 17 from either side adapted to be welded to floors and therefore spaced in accordance with the spacing of the floors. The keel casting has a bottom plate 18 adapted to act as the middle strake at the bottom of the ship. A bottom casting 19 is connected with edges of the plate 18.

45 There is a bottom casting 19 to port and one to starboard secured to the edges of the plate 18, each bottom casting extending to point 20 (shown at port). This bottom casting is provided with the usual longitudinals 21, the limber holes 22 and a portion of a floor 23. These parts are also shown in Fig. 3. Fig. 3

shows how the castings are laid in succession, the casting 19 to be followed by the casting 19^a. After these two castings are in place the tank top casting 24 may be located. Each tank top casting carrying integral longitudinals 25, a portion of the floor 26 and limber holes 27. The portion of the floors 23 of the bottom castings and 26 of the tank top castings meet at a middle line 28 (see Fig. 1) where they are welded and the usual lightening holes may be cast wherever desired. The bottom casting carries also lower halves of side girders 30 and the tank top carries the other portions 31, of the side 70 girders which meet at a middle line shown at 32 where they are welded. The tank top is bent down as shown at 33 preferably after casting and by being cut away from the portion 26 of the floor by means of the oxyacetylene flame or otherwise and are rewelded to the floor in the position shown. The side sections 34 are next assembled. They include integrally the portions 35 of the side frames which are located along one edge 80 of a casting and at their ends rest upon the tank top or tops of the floors 26 as indicated at 36. The side castings carry the usual integral longitudinals 37. The side transverses 35 are further reinforced by brackets 38 welded thereto along the lines 39 and to the tank top at 40, shown also in Fig. 5, and to the deck beams 41 along the line 42. The bilge casting 43 is next added including integrally a portion 44 of a floor, longitudinals and limber holes 45, the joints being formed at 46 to the bottom and side castings. 90

The deck beams 41 of the upper deck rest upon the tops of the brackets 38 and are welded thereto and are integrally cast with the decks 47 and deck longitudinals 48. The deck sections extend from the joint 49 to a joint 50. The shelter deck 51 is cast in a similar form and joined to the margin plates 53 integrally cast on the side castings at a joint at 52. Brackets 54 which may be rolled metal are welded to the deck beams at 55 and to the side transverses at 56 with the ordinary welded joint. 100

It is evident that the system of shipbuilding herein shown is of the longitudinal type which contemplates main transverses and main floors, with other floors in the tank intermediate of the transverses. The floors and transverses are shown in Fig. 1. The intermediate floors shown in Fig. 2, are in three parts, 57, 58, and 59, the first one run-

ning from the stiffener 17 on the keel to the side girder 30-31, the second one from that side girder to the next side girder 30-31 and the third one from the last side girder 5 to the bilge. These castings are welded directly to the side girders, the bottom shell, the tank top, the stiffener 17 and at least to the tops of the longitudinals and preferably to one side of them. These castings are provided with an enlargement 60 also shown in Fig. 3 to form a channel through which to flow the metal. The stiffeners 61, of which there is one at each longitudinal, are cut away from the girder above the bulb 60 as shown at 62 for purposes connected with casting. The bottom and top edges of the stiffener are welded to the longitudinals. The longitudinal of one casting is joined to the longitudinal of the next casting through 20 a transverse frame as shown in Fig. 8. This transverse frame may be a portion of a floor 26, a portion of a transverse 35, or a deck beam 41. The edges of the plates 19 and 19^a in the figure form a V groove adapted to be 25 filled in with welding metal similar to that at 67 in Fig. 13. A dovetail lug having a sectional area of a section of the longitudinal is cast on the frame 23, and lugs 63 having a corresponding resistance to shear are 30 cast on the end of the longitudinal of plate 19. The space between them is filled by welding. Similar lugs and dovetails may be added at 40 if desired. Upon the edges of the plate 19 are cast lugs 68 having a resistance to shear equal to the tensile strength 35 of the plate. Upon the transverse 23 are cast dovetailing lugs 69 reinforced in thickness to compensate for the cut out portions 40 between the dovetails around the lugs 68. The spaces between the dovetails and lugs 45 are filled in by welding as indicated at 71 in Fig. 13. The lugs are continued upon the other side of the transverses 23 by further reinforcements 72 adapted to continue 50 the strength of the lugs over into plate 19^a. Returning again to Fig. 8 it is apparent that a wedge 73 may be driven in between the bottom of the lower lug 63 and the dovetail 69 to separate the two thereby pressing 55 tightly together the bottom of the dovetail 69 and the top of the edge of plating 19 so that during assembly these wedges may be utilized instead of bolting plates together to rigidly connect the edges of the castings for 60 welding.

These dovetailed joints are applied to the joints between the shell castings, to the joints between the deck and tank top castings, to the joints between the keel sections shown in Fig. 4 at 74, and similar welded to any other part of the ship which is subjected 65 to heavy tensile strains. The joints between the upper and lower portions of the floors and between the parts of the transverses and

between the transverse brackets and deck beams may be of the ordinary single V or double V welding. In Fig. 11 is indicated the arrangement of these joints. The keel is shown at 75, a bottom casting at 76, a bilge casting at 77 and a side casting at 78. The dotted lines indicate the frame work inside of the shell. It will be noted that the joints shown in full lines lie along the frames, the object of which is to prevent water pressures or loads from bending the welded joint lengthwise thereof, while the great mass of the joints prevents them from being bent across the joints thereby eliminating from the welded joints fatigue strains which might in time have a damaging effect upon a welded ship. When joints of this character are assembled ready for welding a stud on one end of a joint may be welded and a stud at the other end may be welded to the dovetail, to locate the casting rigidly in position after which the welding of the different studs between may proceed, irregularly if desired. After the dovetailed joints are welded the outside seam may be welded to provide a water tight joint and the welding metal is preferably flattened by a pneumatic hammer, an operation similar to caulking. This, however, is not a necessity unless a leak should develop during test. 95

It is evident that this joint provides a mechanical strength equal to the strength of the plates even though the welding might not adhere to the parent metal. The welding metal in the dovetailed joint is in an undercut groove as shown at 79 so that even if it should get loose it could not escape from the joint, and in case of trouble at sea with a joint the worst that could happen would be a leak through a tiny crevice which could be 105 caulked on the inside of the ship along the dovetails. If the welding is of ordinary strength, however, the welding about the dovetailing exceeds the strength of the plates and the welded seam 67 is nearly equal to 110 that of the plates so that the maximum strength of the joint may exceed three times the strength of the plates. As this joint can be accomplished by an amount of metal that is of insignificant value and by 115 means of ordinary apparatus at comparatively small expense it provides means for joining castings with great speed and little labor.

In Fig. 4 the ends of the keel casting may 120 be united at top and bottom by similar studs and perforations and the joint between the web portions 14 of the keel may be united if desired along the edge 80 by the usual V weld. Clips or stiffeners 61 may be cast integrally with the castings wherever desired. The enlarged spaces 81 shown in Fig. 2 are not necessary but if desired may be filled in by special triangles of metal welded into place if desired. In Figs. 9 and 10 the joint 130

at 82 between the hatchway and deck casting may be similar to that shown in Figs. 12 and 13. A similar joint may also be applied at 83 if desired and at 84 a joint shown in Fig. 5 9 may be applied. A joint of the character shown in Fig. 8 having a plurality of sets of dovetails 64 and lugs 63 may be employed to unite ends of side girders such for example as those illustrated in Fig. 3 at 85 to the 10 clips 61 which may be slightly offset for the purpose. Many variations in the details of construction may be made without departing from the spirit of my invention.

What I claim is:

15 1. A joint between the edges of plates adapted to overlap, the laps being respectively provided with dovetailed lugs and welding grooves between the adjacent edges.

20 2. The combination claimed in claim 1 having said lugs of an area to provide a resistance to shear equal to the tensile strength of the plates and said dovetails being similarly reinforced.

25 3. The combination claimed in claim 1 having a seam upon the joint between said plates upon a side opposite from said lugs and dovetails for welding a water tight seam.

30 4. The combination claimed in claim 2 having a seam upon the joint between said plates upon a side opposite from said lugs and dovetails for welding a water tight seam.

35 5. The combination claimed in claim 1 having a rib or frame along the joint between said plates to stiffen the same.

6. The combination claimed in claim 2 having a rib or frame along the joint between said plates to stiffen the same.

7. The combination claimed in claim 3 having a rib or frame along the joint between said plates to stiffen the same. 40

8. The combination claimed in claim 4 having a rib or frame along the joint between said plates to stiffen the same.

9. In combination a plurality of castings, 45 the edge of one almost but not quite enclosing the edge of another and spaces between them adapted for filling with means to bind the edges together.

10. The combination claimed in claim 9 50 having a dovetail upon one casting having an edge adapted to partly enclose the edge of another casting and a cut out portion adapted to receive a filler to bind the castings together. 55

11. A joint as claimed in claim 1, each plate having a lap in a plane parallel with that of the adjoining plate, said adjoining plate lying in the plane of the first plate.

12. The combination claimed in claim 9 60 to eliminate bolting up of plates and to automatically assemble for welding.

13. The combination claimed in claim 10 to eliminate bolting up of plates and to automatically assemble for welding. 65

14. Castings adapted to be joined end edge to end edge, each casting provided with a joggled lap for an adjoining casting, the overlapping portions being respectively provided with dovetailing means. 70

15. Castings as claimed in claim 14, each having a girder member in the vicinity of the joint.

In testimony whereof, I have affixed my signature to this specification.

MYRON F. HILL.
